UNITED STATES PATENT OFFICE.

CHARLES C. MCCLINTOCK, OF ENGLEWOOD, COLORADO.

TROLLEY-HEAD.

No. 873,955.

Specification of Letters Patent.

Patented Dec. 17, 1907.

Application filed June 25, 1907. Serial No. 380,703.

To all whom it may concern:

Be it known that I, CHARLES C. MCCLINTOCK, a citizen of the United States, residing at Englewood, in the county of Arapahoe and State of Colorado, have invented certain new and useful Improvements in Trolley-Heads, of which the following is a specification, reference being had to the accompanying drawings.

10 My invention relates to improvements in trolley poles and heads, and it consists in the novel construction and the combination of parts hereinafter described and claimed.

15 The object of the invention is to provide a trolley head of simple, strong, durable and inexpensive construction, and one in which the parts may be readily adjusted and separated so that they may be replaced by new parts when broken or worn out.

20 The above and other objects which will appear as the nature of the invention is better understood are attained in the preferred embodiment of my invention illustrated in the accompanying drawings in which

25 Figure 1 is a side elevation of the device; Fig. 2 is a vertical section; Figs. 3 and 4 are sections taken respectively on planes indicated by the lines 3, 3 and 4, 4 in Fig. 2; Fig. 5 is a detailed view of the guard or deflector, 30 and Fig. 6 represents side and sectional views through the locking washer.

In the drawings 1 denotes the usual trolley wheel suitably journaled upon a bolt or shaft 2 arranged transversely in the arms 3 of a 35 fork or yoke 4. The latter has a comparatively broad base from which depends a pivot or spindle 5 journaled in anti-friction bearings in the head or body 6 of the device. This head 6 is in the form of a substantially 40 rectangular block having a rounded forward end formed with a transverse horizontal opening 7 and a square rear end formed with a vertical opening 8 for the spindle 5. Formed in the top and bottom of the body 6 45 concentric with the opening 8 are raceways 9 for the reception of annular series of bearing balls 10. The upper series of balls engages a cone bearing 11 formed upon the upper portion of the spindle and the lower series engage 50 an adjustable cone ring or bearing 12 secured upon the threaded lower end 13 of the spindle as clearly shown in Figs. 2 and 3. In order to insure perfect electrical connections between the trolley 1 and the trolley 55 pole 1 I preferably provide contact springs 14, 15 and 16. The springs 14, 15 are similar

and have their lower ends secured upon the inner faces of the arms 3 of the fork as shown in Figs. 2 and 3 and their upper ends are apertured as at 17 to receive the bolt 2 and 60 are adapted to bear against the sides of the trolley 1. The spring 16 is secured at its forward end upon a lug or projection 18 formed upon the top of the body 6, and the free end of said spring projects between the fork arms 65 3 and bears upon the enlarged base portion of the fork as clearly seen in Fig. 2. Upon reference to said figure it will be noticed that the lug 18 also serves as a stop to limit the rotary movement of the trolley fork 4, but 70 permits the same to have sufficient rotary movement to enable the trolley to properly engage the trolley wire when the car turns a corner. The opening 7 in the body 6 is for the reception of a bolt 19 which adjustably 75 secures the body between the arms 20 of a yoke or fork 21 from the trolley pole 22 and which also serves to adjustably support a wire guard or deflector 23.

Formed upon the side faces of the body 80 concentric with the opening 7 are annular series 24, 25 of radially extending V shaped teeth or serrations. The teeth 24 upon one side are adapted to be engaged by a similar series of teeth 26 formed upon one face of a 85 locking washer 27 which is adapted to receive the bolt 8 and has formed upon its opposite side at diametrically opposite points outwardly projecting fingers 28 adapted to engage the opposite edges of one of the arms 90 20 of the yoke 21. The other series of teeth 25 are engaged by a similar series of teeth 29 formed upon one face of an arm 30 which is connected to and supports the deflector 23. The body of the latter is preferably in the 95 form of a straight bar which is arranged in an upwardly and rearwardly inclined position so that its lower end projects into the yoke 21 and its upper end terminates beneath the top of the trolley wheel 1 as shown 100 in Figs. 1 and 2. It will be seen that by providing the teeth 24, 25 on the body 6 and the teeth 26, 29 on the washer 27 and the deflector, respectively, and arranging said washer and deflector on the opposite sides of 105 the body, the nut 31 of the bolt 19 when tightened will effectively clamp said parts together and between the arms 20 of the yoke 21. When the nut 31 is loosened it will be seen that the body 6 may be swung 110 vertically upon the bolt 7 and that the deflector 23 may be similarly adjusted in a ver-

tical plane. It will be also noted that this connection is simple, strong and durable and that it permits the parts to be readily separated for adjustment, repairs and the like.

5 From the foregoing detailed description, taken in connection with the accompanying drawings it is thought that the construction, operation and advantages of the invention will be readily understood without a more 10 extended explanation.

Having thus described my invention, what I claim as new, and desire to secure by Letters Patent is:—

1. The combination with a trolley pole, of 15 a trolley wheel carried thereby, a deflector for the wheel pivoted for swinging movement toward and from the wheel, and a fastening member for clamping said deflector rigidly in an adjusted position with respect 20 to the wheel, substantially as described.

2. The combination with a trolley pole having a yoke, of a head or body carrying a trolley wheel, a deflector, and a fastening 25 passed through said yoke, said head and said deflector for adjustably connecting the same, substantially as described.

3. The combination with the trolley pole having a yoke formed with apertured arms, of a head or body carrying a trolley wheel

and formed with an aperture and with serrations arranged on the opposite sides of said body adjacent to its aperture, a washer having projections to engage one of the arms of the yoke and serrations to engage the serrations on one face of the head, a deflector having an arm formed with an aperture and with serrations adapted to engage the serrations on the other face of said head and a bolt passed through the apertures or openings in said yoke, said washer, said head and said 40 deflector, substantially as and for the purpose set forth.

4. The combination with a trolley pole, of a head or body carried by the pole, a trolley wheel mounted upon said head or body, a 45 deflector for the wheel provided with an arm having serrations to engage said head or body and a pivot fastening passed through the arm of the deflector and into said head or body to adjustably clamp said arm upon the 50 latter, substantially as described.

In testimony whereof I hereunto affix my signature in the presence of two witnesses.

CHARLES C. MCCLINTOCK.
